VERMIN DESTROYING APPARATUS

Filed Feb. 5, 1923

FIG. 2.

FIG. 3.

Inventor
Julius Stein
By his Attorney
[Signature]

UNITED STATES PATENT OFFICE.

JULIUS STEIN, OF NEW YORK, N. Y.

VERMIN-DESTROYING APPARATUS.

Application filed February 5, 1923. Serial No. 617,136.

To all whom it may concern:

Be it known that I, JULIUS STEIN, a citizen of the United States, and a resident of New York city, in the county of the Bronx and State of New York, have invented certain new and useful Improvements in Vermin-Destroying Apparatus, of which the following is a full, clear, and exact description.

10 Among the principal objects which the present invention has in view are: To exterminate the vermin which infest articles of furniture, and especially beds; to place the material for the extermination of the vermin referred to in a position to attract said vermin; to render the preparation and handling of the apparatus easy; and to cheapen the construction of the same.

Drawings:

20 Figure 1 is a top plan view of a corner fragment of an iron mattress for a bed, showing an apparatus of the character mentioned constructed and arranged in accordance therewith, attached as in service to said mattress;

25 Figure 2 is a detail view on enlarged scale, showing an edge view of the apparatus; a portion of the figure is cut away to show the interior construction of the apparatus.

30 Figure 3 is a cross section of the same, the section being taken as on the line 3—3 of Figure 2.

35 The apparatus herein disclosed is particularly designed for the extermination of vermin which infest beds. To this end the frame 8 is provided with anchoring means, such as the soft overturning bands 9. The bands 9 when extended between the wires of 40 the mesh 10 of the mattress may be overturned as seen best in Figure 1 of the drawings to form the support for the apparatus.

45 As seen best in Figure 3 of the drawings, the frame 8 has edge flanges 11 and inwardly extended therefrom sections 12, from which are formed the pans 13. The pans 13 are provided, as shown in Figure 1 of the drawings, and are furnished with a poison bait 14 of any desired kind, which 50 when partaken of by the vermin destroys them. The bait 14 is intentionally constructed of a character to produce thirst in the vermin or desire to reach some form

of liquid. For this purpose a well 15, which is a tubular container having venting openings 16 therein, is supported on the frame 8. The well 15 is open at the top and is provided with laterally extending flanges 17 which rest upon the inturned and slightly dropped flanges 18 of the frame 8.

55 To prevent the well going dry, an absorbent pad 19 is provided in the bottom of the well 15.

60 In some instances the liquid provided for filling the well 15 has a pungent odor which expels or kills the vermin from or within the vicinity of the wells or apparatus.

65 To close the well 15 and to confine partly or wholly the odors of the liquid contained therein, a slide plate 20 is provided. The 70 plate 20 has a series of openings 21 which are enlarged or diminished by the movement of the plate 20, thus in turn increasing or diminishing the odors permitted to escape from the well 15. The openings 21 also 75 afford opportunity for the vermin to gain access to the well.

Claims:

1. A vermin destroying apparatus comprising a tray-like receptacle having a series 80 of pans formed therein for holding poison bait; a liquid receptacle suspended from said tray-like member; and means for mounting the apparatus in service upon a spring mattress of a bed.

85 2. A vermin destroying apparatus comprising a tray-like member having a plurality of pans formed thereon for holding poison bait; a receptacle for liquid removably mounted on said tray-like receptacle; 90 and means for mounting the same in service upon the spring mattress of a bed.

3. A vermin destroying apparatus comprising a tray-like member having a plurality of pans formed thereon for holding poison bait; a receptacle for liquid removably mounted on said tray-like receptacle; 95 means for mounting the same in service upon the spring mattress of a bed; and means for regulating the opening of said receptacle, said means embodying a sliding plate having openings therein to be determined by the side of the receptacle over which said plate is moved.

JULIUS STEIN.
